UNITED STATES PATENT OFFICE.

JOHN SINNAMON, OF OSWEGO, NEW YORK.

PILLOW-BLOCK.

SPECIFICATION forming part of Letters Patent No. 240,046, dated April 12, 1881.

Application filed February 4, 1881. (No model.)

To all whom it may concern:

Be it known that I, JOHN SINNAMON, of Oswego, Oswego county, New York, have invented an Improvement in Pillow-Blocks, of 5 which the following is a specification.

This invention relates to pillow-blocks for the crank-shafts or main driving-wheel shafts of horizontal reciprocating engines. The journal-bearings of such shafts are subject to great 10 wear at their sides, and liable to produce lost motion and thumping or pounding of the shaft. To overcome this difficulty various devices have been resorted to, one of the most effective of which is the employment of adjustable wedges applied to the back of the 15 side bearings or followers for the purpose of compensating for the wear of the journal-bearing and taking up the lost motion. It is this latter class of pillow-blocks to which my invention pertains; and it consists in certain peculiar features in the detail construction of the pillow-block and the appliances for compensating for the aforesaid wear, all as hereinafter fully described, and specifically set forth in 20 the claims.

In the accompanying drawings, Figure 1 is a transverse section of my improved pillow-block; Fig. 2, a top view of same, and Fig. 3 a longitudinal section on line $x x$ in Fig. 1. 25 Similar letters of reference indicate corresponding parts.

P denotes the pillow-block, provided with vertical jaws J, between which and the cap C the journal-box is confined. The journal-box 30 is composed of four brasses or anti-friction metal bearings, A A and B B, arranged respectively at the two sides and at the top and bottom of the journal, said bearings having between their adjacent edges a space, v , which 35 allows them to be moved inward and set up to the journal according to the wear on the bearings, the spaces v also forming lubricating-channels, which may be filled with suitable packing for containing the lubricant. The 40 bearings B B are fitted in collars or recesses r , respectively in the upper side of the bottom portion of the pillow-block and in the under side of the cap C. The side bearings A rest on the interior bottom of the pillow-block, and are held by a downward projection, 45 d , on the under side of the cap C resting on

top of the bearing A. The back of the bearing A is outwardly inclined or tapered from the base of the journal-box upward, and between it and the jaw J of the pillow-block is interposed a wedge, w , which is tapered toward the base of the journal-box and arranged movable vertically or at right angles to the axis of the journal-box in an elongated seat, e , formed partly by a recess in the base of the 55 pillow-block adjacent to the jaws J and partly by the projection d on the under side of the cap C. The pressure of the wedge w against the bearing A moves the latter inward and sets it, with a uniform pressure throughout its 60 length, up against the journal, according to the wear of said bearing. The said adjustment is accomplished by means of a set-screw, a , which has a smooth body passing loosely or freely through the cap C, and engages with 65 its threaded lower extremity a correspondingly-threaded socket, s , in the center of the top of the wedge w , thus holding the said wedge in a suspended position by the head of the screw a resting on top of the cap C. Two 70 other set-screws, $b b$, working in threaded holes in the cap C, and bearing with their lower extremity on the wedge w , near the ends thereof, serve to hold said wedge in position. By releasing the set-screw a and tightening the set-screws b the wedge w is forced downward and caused to press the bearing A inward against 75 the journal, as may be required to compensate for the wear of said bearing.

I do not claim, broadly, the employment of 80 wedges at the back of the side bearings for the purpose of setting up said bearings and compensating for the wear of same, as I am aware the same is not new; but

What I do claim as my improvements is— 85

1. In combination with the pillow-block jaws J and cap C, the side bearings, A, tapered from the base of the journal-box upward, the wedge w , arranged movably at right angles to the axis of the journal and tapered toward the 90 base of the journal-box, the suspending-screw a , having a blank neck through the cap and engaging with its threaded lower extremity, a threaded socket central in the top of the wedge, and the set-screw $b b$, working in threaded 95 holes in the cap C, and bearing with their lower ends on top of the wedge, near the two 100

ends thereof, substantially in the manner described and shown.

2. The combination of the pillow-block P, provided in the upper side of its bottom part 5 with the recess *r* at the center, and with recesses *e* adjacent to the jaws J, the cap C, provided with the central recess, *r*, and downward projections *d*, the bearings A, held between said projections and interior bottom of the pillow-block, the bearings B, seated in the recesses *r*, the wedges *w*, interposed between the bearings A and jaws J, and the set-screws *a*

and *b*, inserted through the cap, all combined and arranged substantially in the manner described and shown.

In testimony whereof I have signed my name and affixed my seal, in the presence of two attesting witnesses, at Oswego, in the county of Oswego and State of New York, this 28th day of January, 1881.

JOHN SINNAMON. [L. s.]
